PEBBLE FLOW CONTROL

Carl E. Alleman, Etter, Tex., assignor to Phillips Petroleum Company, a corporation of Delaware

Application May 1, 1956, Serial No. 159,350

14 Claims. (Cl. 23—288)

This invention relates to apparatus and process for regulating flow of a contiguous flowable mass of particulate solids. In one embodiment this invention relates to the regulation of pebble flow through a pebble heater system.

Various means have been proposed in the art for regulating flow of a contiguous flowable mass of particulate solids. Typical of such well-known means are those involving screw conveyors, star valves, and similar devices utilizing continuously moving parts. Such devices are necessarily fabricated of special alloys offering the necessary resistance to strong abrasive effects of the moving solids on the moving parts, and to provide resistance to wear from movement of the parts. Such fabricating materials are costly and depreciate at a high rate and are expensive to maintain. Furthermore, a temperature at which such devices can be operated is limited generally to a level not higher than from about 600 to 800° F. by virtue of the increase in the amount of wear on the moving parts incurred at those maximum permissible temperatures. Another limitation on the temperature at which such devices can be utilized is the tensile strength of the material which, of course, decreases with increasing temperatures.

My invention is concerned with process and apparatus for controlling flow of a contiguous flowable particulate mass of solids, wherein no continuously moving equipment parts are required, and the flowing solids can be handled at temperatures as high as from 800 to 1200° F. or higher. My invention further provides for the use of more readily available and relatively inexpensive fabricating materials in controlling such solids flow than can be used in the construction of a solids flow controller involving the use of continuously moving parts.

Although my invention is well applied to the regulation of the rate of flow of a flowable contiguous particulate mass of solids through a solids system of any kind, it is particularly advantageous as applied to the control of flow of such solids while at a temperature as high as from 800 to 1200° F., and in many instances higher. Accordingly, I have applied my invention in a preferred embodiment to the control of pebble flow through a pebble heater system, wherein in many instances it is advantageous to regulate the pebble flow while handling flowing pebbles at temperatures as high as from 800 to 1200° F. or higher.

A pebble heater system, or pebble heater apparatus as it is often referred to, usually comprises a series of substantially vertically-extending zones, often in vertical alignment with each other. Usually two such zones are employed and are connected by a relatively narrow interconnecting zone, or throat. The top or upper zone is commonly referred to as the pebble heating chamber and the lower zone as the gas reaction or gas heating chamber. A combustion zone, or chamber, is positioned adjacent or in close proximity to the sides of the lower portion of the heating chamber. Combustion gas from

2

a combustion chamber is passed through the mass of pebbles in the pebble heating chamber. A hot gas source other than a combustion means is sometimes employed. A contiguous mass of particulate contact material, often referred to as pebbles, fills the pebble heating zone, the interconnecting zone or throat, and the gas reaction or heating zone, and flows downwardly through these zones by gravity. Pebbles are discharged from the bottom of the gas reaction zone at a controlled rate, and returned, usually by elevating means, to the inlet in the upper portion of the pebble heating zone. A contiguous moving pebble mass thereby fills the pebble heating zone, gas heating zone, and the interconnecting zone, or throat, at all times.

The term "pebbles," as used throughout the specification, denotes any solid refractory material of flowable form and size that can be utilized to carry heat from one zone to another. Pebbles are preferably substantially spherical and about $\frac{1}{32}$ inch to 1 inch in diameter, the preferred range being about $\frac{1}{4}$ inch to $\frac{1}{2}$ inch. Pebbles are formed of a refractory material which will withstand temperatures at least as high as the highest temperature attained in the pebble heating chamber, and must be capable also of withstanding temperature changes within the apparatus. Refractory materials such as metal alloys, ceramics, or other satisfactory material may be utilized to form such materials. Silicon carbide, alumina, periclase, thoria, beryllia, Stellite, zirconia, and mullite may be satisfactorily used to form such pebbles or may be used in admixture with each other or with other materials. Pebbles formed of such materials, when properly fired, serve very well at high temperatures. Some pebbles, such as mullite-alumina pebbles, withstand temperatures up to about 3500° F. Pebbles which are used may be either inert or catalytic, as used in any selected process.

Pebble heater apparatus is generally employed in the thermal treatment or conversion of reactant materials, often hydrocarbons. Operation of such a pebble system generally involves circulating a contiguous pebble mass through the pebble heating chamber, interconnecting throat and reaction chamber. That portion of the pebble mass descending through the heating chamber is heated to a suitable predetermined temperature above a desired treating or conversion temperature in heat exchange relation with combustion gas or other hot gases from any desired source. Pebbles are often heated in the heating chamber to temperatures as high as from 2,000 to 3,000° F., and in some cases higher, dependent upon the temperature requirements of the subsequent treating step. The thus heated pebbles passing through the reaction chamber are contacted directly with the material to be treated or converted for a suitable contacting time to effect the desired treatment. The pebble mass having given up heat to the material treated in the treating zone, descends through the bottom of the reaction chamber and is fed to an elevator for further handling, generally for transfer to an inlet at the top of the pebble heating chamber for reheating and recirculation through the system.

An object of my invention is to provide process and apparatus for regulating flow of a contiguous flowable particulate mass of solids.

Another object is to provide apparatus for regulating flow of a flowable contiguous mass of particulate solids while at a temperature as high as 1200° F. or higher.

Another object is to provide apparatus free of continuously moving parts for regulating the flow of a contiguous flowable mass of particulate solids.

Another object is to provide process and apparatus for controlling the flow of pebbles through a pebble heater system.

Other objects will be apparent to those skilled in the art from the accompanying discussion and disclosure.

Broadly, the apparatus of my invention comprises a fluent solids reservoir; a fluent solids inlet conduit extending into the reservoir, and terminating therein, and in communication at its other end with a source of a contiguous mass of flowable particulate solids; and a fluent solids outlet conduit extending downwardly from a point inside the reservoir intermediate a point inside a zone defined hereafter and a point outside that zone, to a point outside the reservoir. The zone portion above referred to is an imaginary cone based on the horizontal, having the outlet end of the solids inlet conduit at its apex and having an apex angle generally within the limits of from about 90 to 140°, although in most instances within a narrower range of 100 to 130°. The value of the apex angle is not unconditionally within the limits above specified, but is dependent upon the size, shape, surface, and the like, of the solid particles being handled, as discussed in more detail hereafter. The upper end of the outlet conduit is out of vertical alignment with the outlet end of the solids inlet conduit. Either or both of these conduits, as desired, are adjustably movable to regulate the position of the outlet conduit with respect to disposing its upper end at a predetermined point intermediate the points respectively inside and outside the imaginary zone discussed above.

In a broad embodiment of the process of my invention, a stream of contiguous flowable particulate solids is passed into the solids reservoir through the solids inlet conduit. A solids mass is gravitationally formed in the reservoir and tends to assume the shape of a horizontally based cone having the outlet end of the solids inlet conduit at its apex. The size of the apex angle is dependent on the "angle of repose" of the solids mass in the reservoir, i. e. the angle formed between the upper surface of the solids mass and the horizontal, above which the solids will not flow from the solids inlet into the reservoir gravitationally, but below which solids flow by gravity from the downstream end of the solids inlet conduit into the reservoir. Usually the angle of repose for a contiguous mass of solids is within the limits of from about 20° to 45°, dependent on the shape, size, and surface characteristics of the solid particles. Obviously, the greater the size and the more irregular the shape and surface of the solid particles, the greater the angle of repose, and conversely the smaller the particle size and the more regular the shape and surface characteristics of the particles, the less the value of that angle.

When the position of either or both conduits is regulated as above described, the position of the upper end of the outlet conduit is accordingly altered with respect to the surface of the solids mass in the reservoir. When the inlet conduit is extended downwardly while the outlet conduit is stationary the surface of the solids mass in the reservoir is lowered and the upper end of the outlet conduit is in effect raised, and conversely, if the inlet conduit is raised, the height of the pebble mass is increased and the upper end of the outlet conduit is in effect lowered. When the outlet conduit is adjustably moved in a downward or upward direction, its upper end will, of course, be disposed accordingly with respect to the surface of the solids mass. Obviously then, one of these conduits can be adjustably moved with the other fixed, or both can be moved at the same time to dispose the upper end of the outlet conduit at a predetermined point with respect to the surface of the solids mass in the reservoir. Also, it is obvious that the position of the upper end of the outlet conduit, with respect to the lower end of the inlet conduit, will be varied as the respective conduits are raised or lowered.

When the upper end of the outlet conduit is above the surface of the solids mass, no solids flow can occur. As the position of the outlet conduit is lowered, with respect

to the surface of the solids (by moving either conduit), a point is reached at which some solids can roll into the outlet conduit. Depending upon the nature of the solids and the size and shape of the opening in the upper end of the conduit, solids flow will occur at a certain rate for any given position of the conduits. Solids will flow at a higher rate as the relative position of the outlet conduit is lowered. Ultimately, the position of the outlet conduit, relative to the end of the inlet conduit and the surface of the solids, can be such that the outlet conduit is flowing "solids full" and no further increase in flow rate is possible. Such a position is reached when the upper end of the outlet conduit is well below the surface of the solids mass and directly, or nearly directly, below the lower end of the inlet conduit.

The accompanying drawings illustrate preferred forms of apparatus and process of my invention, and are discussed with reference to controlling a flow of pebbles. It is to be understood, however, that my invention is also well applied to the control of flow of contiguous flowable solid particulate materials of any type, and that various modifications of the illustrated process and apparatus can be made and still remain within the scope of my invention. Figure 1 is a transverse sectional view of an apparatus embodying my invention wherein both the inlet and outlet conduits are vertically disposed in the solids reservoir and offset from each other. Figure 2 is a sectional view similar to that of Figure 1, except that the inlet and outlet conduits are not necessarily vertically disposed. Figures 3A, 3B, 4A, and 4B illustrate modified forms of the outlet conduit of Figures 1 and 2 that can be utilized. Figure 5 is illustrative of apparatus of my invention as applied to controlling a flow of pebbles through a pebble heater system.

Referring to Figure 1, pebble inlet conduit 10 extends vertically downward through sleeve 11 into pebble reservoir 12, and is in communication at its upper end with pebbles in a pebble heater system. Conduit 10 is axially adjustable and can be moved in an axial direction through sleeve 11 by means of rack and pinion means 13. Conduit 10 terminates in reservoir 12 to admit pebbles to form pebble mass 14 having a conical upper surface with the outlet end of conduit 10 at the apex and an apex angle within the limits of about 90 to 140°, dependent upon the size, shape, and surface characteristics of the pebbles therein. In most instances the angle of repose of the pebbles lies within a range of from 25 to 40° and thus the apex angle will generally be within the limits of from 100 to 130°. Outlet conduit 16 is vertically disposed and extends into reservoir 12 through sleeve 17 and is axially adjustable. Conduit 16 can be moved in an axial direction through sleeve 17 by means of rack and pinion means 18. The upper end 19 of conduit 16 can be disposed completely within pebble mass 14, i. e. below surface 20, in which case flow of pebbles through conduit 16 is substantially unrestricted, or it can be disposed completely above surface 20, in which case pebble flow from mass 14 into conduit 16 is completely terminated. When end 19 is disposed so that a portion of its cross-sectional area is within mass 14 and the remaining portion is in space 21, a proportionate degree of flow of pebbles from mass 14 into conduit 16 is effected. In other words, depending upon the proportion of the cross-sectional area of upper end 19 of conduit 16 in the region where pebble flow can occur, the rate of flow of pebbles into conduit 16 can be regulated. After the selected rate of pebble flow is established the position of conduit 16, with respect to pebble mass 14, is not disturbed and the flow continues at the predetermined rate over any desired operating period without the need for any moving equipment parts of any kind.

As shown in Figure 1, both conduits 10 and 16 are movably adjustable in an axial direction. It is to be understood, however, that although both conduits can be

moved in an axial direction when determining the final position of upper end 19 of conduit 16 with respect to the surface 20 of pebble mass 14, I prefer generally to maintain one of these conduits in a fixed position and to axially move the other conduit with respect to that fixed position. Accordingly, in one embodiment, conduit 10 is rigidly attached to reservoir 12 and conduit 16 is axially movable as shown; and in another embodiment the converse is true, i. e. conduit 16 is rigidly disposed and conduit 10 is axially adjustable.

As illustrated in Figure 2, it is not necessary that conduits 10 and 16 be each vertically disposed. Conduit 10 can extend into reservoir 12 at any desired angle, the tendency of mass 14 to form a horizontally based cone with pebble inlet conduit 10 at its apex being the same regardless of the angle at which conduit 10 is disposed. Similarly, conduit 16 is not necessarily vertically disposed, but can be disposed downwardly from the interior of zone 12 at any desired angle. However, in order for the full capacity of conduit 16 to be utilized in conducting pebble flow, it must be disposed at an angle with the horizontal greater than about 40°, since it has been found that such a conduit disposed at a smaller angle cannot carry full pebble flow. In any case, the inlet end 19 of outlet conduit 15 is adapted to be disposed out of vertical alignment with the outlet end 9 of inlet conduit 10. Expressed in another manner, the longitudinal axis of conduit 16 is out of vertical alignment with the outlet end 9 of conduit 10.

I prefer to employ a single conduit 16 having a cross-sectional area substantially the same as that of conduit 10, so that when conduit 16 is axially moved to dispose its upper end 19 completely within the pebble mass 14, substantially unrestricted flow of pebbles will occur from conduit 10. However, if desired, a finer control of flow from conduit 10 can be effected by employing a plurality of conduits 16 having a total cross-sectional area as desired, but preferably about the same as that of conduit 10. In this manner any inherent manipulative error can be substantially reduced in controlling the pebble flow rate.

As illustrated in Figures 3a and 3b, the end 19 of conduit 16 can be beveled to permit a larger proportion of its area to be available to pebbles in the region where pebble flow can occur, thereby increasing to a significant degree the accuracy in adjusting the position of upper end 19 with respect to surface 20 of pebble mass 14 to establish the desired rate of pebble flow from conduit 10. As illustrated in these figures, the beveled end portion can directly face the flowing pebbles or it can be disposed at an angle to the line of such pebble flow. Similarly, Figures 4a and 4b further illustrate the apparatus embodiment of my invention wherein the upper end 19 of conduit 16 is beveled.

With reference to Figure 5, pebble heater apparatus 22 consists of pebble heating chamber 23, gas reaction chamber 24, throat 26 interconnecting chambers 23 and 24, pebble outlet conduit 27, pebble inlet conduit 28, pebble elevating means 29, inlet conduit 31 for admitting combustible gases into combustion chamber 32, flue gas outlet 33, reactant gas inlet 34, and product gas outlet 36. Pebble inlet conduit 10 of pebble flow controller 37 is axially disposed with conduit 27 and in communication with pebbles passed through the bottom of chamber 24 into conduit 27. Conduits 10 and 16 extend into reservoir 12 in any manner, as discussed hereinabove with respect to Figures 1, 2, 3a, 3b, 4a, and 4b. Conduit 16 is connected with elevator inlet conduit 38 for discharge of pebbles from pebble mass 14 in reservoir 12, into elevator 29, whereby the pebbles discharged through line 16 are recycled to the pebble heater system for recirculation.

In the operation of the embodiment illustrated in Figure 5, a combustible gas mixture is introduced through

line 31 into combustion chamber 32, and burned therein to provide a combustion temperature generally as high as about 2,000 to 3,000° F. or higher. Combustion gas thus formed is passed upwardly through chamber 23 in heat exchange relation with a downwardly flowing contiguous mass of pebbles therein to heat same to a temperature above a predetermined conversion temperature. Combustion gases having imparted heat to pebbles in chamber 23, are withdrawn through conduit 33. The heated pebble mass flowing downwardly through throat 26 is passed through reaction chamber 24 in countercurrent flow and heat exchange relation with a reactant gas, often a hydrocarbon, introduced into chamber 24 through conduit 34, whereby the reactant is heated to the conversion temperature and conversion product is formed. Conversion product is withdrawn from chamber 24 through conduit 36. Pebbles having imparted heat to the reactant materials are discharged from chamber 24 through line 27 into inlet conduit 10 of pebble flow controller 37.

In pebble heater operation, it is generally necessary that the temperature of the pebbles discharged be not above a maximum often from 500 to 800° F. for the reason that the controller means is not operable for long periods when utilized for handling pebbles at higher temperatures, as discussed hereinabove. However, it is often advantageous that the temperature of the pebbles discharged from chamber 24 be higher than 800° F., and often as high as 1200° F., dependent upon the specific conversion process conducted in pebble heater system 22, as for example in cracking light hydrocarbon gases such as ethane or propane. As provided for by my invention, the temperature of pebbles introduced into pebble reservoir 12 from conduit 10 and discharged through line 16 can be considerably higher than the 800° F. limit discussed hereinabove, being as high as 1200° F., or higher when desired. This is possible to a large extent because the fabricating materials of controller 37 can be highly insulated or can be completely ceramic, thus providing for the handling of pebbles at temperatures far exceeding 1200° F., and for the further reason that there are no continuously moving parts involved in the structure of flow controller 37.

The rate of flow of pebbles through pebble heater system 22 is regulated by controller 37 at a predetermined constant level for over any desired operating period without interruption of any kind.

As will be evident to those skilled in the art, various modifications can be made or followed, in the light of the foregoing disclosure and discussion, without departing from the spirit or scope of the disclosure or from the scope of the claims.

I claim:

1. Apparatus for regulating the flow of pebbles through a pebble heater system, comprising a pebble chamber, said chamber being completely closed except for a pebble inlet conduit and a pebble outlet conduit therefor; said pebble inlet conduit extending downwardly into said chamber and terminating therein; a pebble mass in said chamber having a conical upper surface and having its apex at the lower end of said inlet conduit; said pebble outlet conduit extending downwardly from the interior of said chamber to an external point and having its upper end out of vertical alignment with the terminated end of said inlet conduit; at least one of said conduits being longitudinally movable; and means for longitudinally moving such a conduit so as to dispose the upper end of said outlet conduit at a predetermined point intermediate a point in said mass and a point in said chamber above the upper surface of said mass.

2. An improved pebble heater apparatus, comprising a pebble heating chamber; a reaction chamber positioned below said heating chamber; a pebble throat conduit interconnecting said heating chamber and said reaction chamber; said chambers and said throat containing a

contiguous mass of pebbles; means for introducing hot heat exchange gases in contact with pebbles in said heating chamber; pebble inlet means in an upper portion of said heating chamber; gas outlet means in an upper portion of said heating chamber; gas inlet means and effluent gas outlet means in said reaction chamber; a pebble receiving chamber below said reaction chamber, said receiving chamber being completely closed except for a pebble inlet conduit and a pebble outlet conduit therefor; said pebble inlet conduit extending downwardly into said receiving chamber so as to convey gravitational flow of pebbles from said reaction chamber into said receiving chamber; a pebble mass in said receiving chamber contiguous with pebbles in said reaction chamber, and having a conical upper surface and its apex at the lower end of said inlet conduit; said pebble outlet conduit extending downwardly from the interior of said chamber to an external point and having its upper end out of vertical alignment with the outlet end of said inlet conduit; at least one of said pebble inlet and pebble outlet conduits being longitudinally movable; and means for longitudinally moving such a longitudinally movable conduit so as to dispose the upper end of said outlet conduit at a point intermediate a predetermined point in said mass and a point in said chamber above the upper surface of said mass.

3. A process for regulating flow of pebbles through a pebble heater system, comprising gravitating a stream of pebbles from such a system into a pebble receiving zone through a first conduit extending downwardly into said zone, and forming a pebble mass therein contiguous with pebbles in said pebble heater system, conveying by gravitational flow only, pebbles from said mass through a second conduit extending into said mass and downwardly away from said receiving zone and spaced out of vertical alignment with said first conduit, and controlling the rate of gravitational flow of said pebbles by varying the degree to which said second conduit extends into said mass.

4. The process of claim 3 wherein said gravitational flow of pebbles is conveyed in a lateral direction from said pebble mass.

5. The process of claim 3 wherein said gravitational flow is conducted in a substantially vertical direction from said pebble mass.

6. The process of claim 3 wherein said rate of gravitational flow of pebbles is controlled by varying the proportion of the area of the upper end of said second conduit in contact with pebbles flowing from said mass.

7. A process for regulating flow of fluent solids through a solids handling system, comprising gravitating a stream of solids from such a system into a solids receiving zone through a first conduit extending downwardly into said zone and forming a solids mass therein contiguous with solids in said solids system, conveying by gravitational flow only, solids from said solids mass through a second conduit extending into said mass and downwardly away from said receiving zone and spaced out of vertical alignment with said first conduit, and controlling the rate of gravitational flow of said solids by varying the degree to which said second conduit extends into said mass.

8. Apparatus of claim 1 wherein only said inlet conduit is longitudinally movable.

9. Apparatus of claim 1 wherein only said outlet conduit is longitudinally movable.

10. Apparatus of claim 1 wherein both said inlet and outlet conduits are longitudinally movable.

11. The apparatus of claim 1 wherein each said conduit is vertically disposed.

12. The apparatus of claim 1 wherein said upper end of the outlet conduit is cut at an angle other than perpendicular to the axis thereof.

13. The apparatus of claim 1 wherein said inlet conduit is vertically disposed and said outlet conduit is disposed angularly through a side wall of said chamber.

14. The apparatus of claim 1 wherein one of said conduits is adjustably secured to said chamber, and the other of said conduits is rigidly secured to said chamber.
